CLAIM

The ornamental design for a faucet, as shown and described.

DESCRIPTION

FIG. 1 is a left, top, front perspective view of a faucet embodying our new design;

FIG. 2 is a front elevational view thereof;

FIG. 3 is a rear elevational view thereof;

FIG. 4 is a top plan view thereof; and,

FIG. 5 is a right side elevational view thereof, the left side elevational view being a mirror image of the right side shown.

The broken line representation of a platform in FIGS. 1-4 is for the purpose of illustration only, and forms no part of the claimed design.
